UNITED STATES PATENT OFFICE.

GEORGE H. SPENGLER, OF ROCKFORD, ILLINOIS, ASSIGNOR TO FRANK VANDER BOGART, OF ROCKFORD, ILLINOIS.

PUNCH.

Application filed May 31, 1924; Serial No. 716,863.

To all whom it may concern:

Be it known that I, GEORGE H. SPENGLER, a citizen of the United States, residing at Rockford, in the county of Winnebago and State of Illinois, have invented certain new and useful Improvements in Punches, of which the following is a specification.

This invention relates to metal-working punches in which the punch element may be operated either by hand or power and in the present embodiment is applied to a hand-operated punch of the type disclosed in Reissue Letters Patent No. 13,313 and in my co-pending application Serial No. 672,715. My invention while not limited to this particular form of punch is nevertheless fully exemplified in connection therewith. This type of punch is characterized by the head having integral therewith a punch-guiding jaw, a die-carrying jaw and a handle, and a coacting handle lever pivoted on the head and connected through a power-multiplying device to the punch for moving it toward and from the die. In view of the heavy punching pressure and the short travel of the punch the punch-guiding and die-carrying portions must necessarily be carried in close, coaxial and rigid relative relation and therefore they impose a limitation on the size of work pieces which may be passed between them. Consequently these punches have heretofore been used primarily for punching flat material of limited gage.

The primary purpose of the present invention is to provide an improved punch of this kind in which larger and more irregular work pieces may be inserted between said punch-guiding and die-carrying portions, in which the structure will effectually carry the punch and die without deflection or disalignment under the heavy punching pressures, and in which the die-carrying portion is releasably held in its operative position and may be quickly and easily withdrawn therefrom so as to widen the work-receiving opening.

Other objects and attendant advantages will be appreciated by those skilled in this art as the invention becomes better understood by reference to the following description when considered in connection with the accompanying drawings, in which—

Figure 1, is a side elevation of a punch embodying my invention; 55

Fig. 2, is a top view of the supplemental lower jaw removed from the punch; and Figs. 3, 4 and 5 are detail sections taken on the lines 3—3, 4—4 and 5—5 respectively of Fig. 1; 60

Referring more particularly to the drawing, it will be observed that the punch includes a head designated generally by the reference character 6 having formed integrally therewith an upper and lower jaw 7 and 8 respectively, and a handle 8. A supplemental lower jaw designated generally by 9 pivoted to the lower jaw 8 as will be presently more fully described, carries a die or anvil 11 in alignment with a punch 12 slidable in the upper jaw 7 toward and from the die. The punch is adapted to be moved in a pressure or punching stroke and in a return or retracting stroke through the agency of a punch-moving part 13 and an operating lever 14. The part 13, pivoted at 15 on the head 6, has a T-shaped recess or slot 16 in its outer end adapted to receive the T-head 17 of the punch, as shown in Fig. 3. The punch element is thus detachably connected to the part 13 and the latter may be swung in a clockwise direction on its fulcrum, viewing Fig. 1, to withdraw the punch from the upper jaw 7. The operating lever 14 is interposed between a pair of side plates 18 and 19 and fulcrumed thereon by means of a bolt 21 which also serves to hold said side plates together. Said side plates in turn straddle the upper jaw 7 and are pivotally attached thereto by means of a bolt 22. A guide pin 23 connecting the side plates and passing through a guide slot 24 in the upper jaw 7 limits the amount of oscillation of the side plates about the bolt 22. On the outer end of the punch-moving part there is provided an upstanding projection 25 circular in cross section, which fits into a complementary recess 26 in the operating lever. By reason of this construction 90

powerful pressure may be transmitted to the part 13 and consequently to the punch 12 for moving the latter in the punching stroke by downward pressure of the operating lever 14, and by raising said lever the punch will be retracted. A suitable 95

spring 27 is interposed between the upper jaw 7 and the part 13 for aiding in retracting the punch.

It will now be observed that the upper 5 and lower jaws 7 and 8, integral with the head 6, are spaced apart so as to provide a relatively wide mouth for disposal of the work between said jaws. The head is reinforced around said mouth through the 10 area of greatest stress by a flange 27 and is shaped below said flange to provide a broad flat bearing surface 28 reaching from the foremost end of the lower jaw to the rear-most end of the head proper. Against this 15 bearing surface 28 the supplemental jaw 9 is held by a heavy pivot bolt 29, it being observed that the body of said jaw is in the form of an elongated bar rectangular in cross section bearing against said broad flat 20 surface 28 from end to end thereof. Said supplemental jaw has formed on its forward end an upstanding die-carrying portion 31 which is disposed in alignment with the punch-guiding portion 32 of the upper jaw. 25 The die-carrying portion 31 is bored from end to end and internally threaded as shown in Fig. 3 for carrying the threaded die element 11 which may be adjusted axially in said bore as will be obvious. It will be ob- 30 served that the die-carrying portion 31 ex- tends within close proximity to the punch- guiding portion 32 so as to support the die in proper relation to the punch and conse- 35 quently provides a restricted mouth or passage between the punch and die. This restricted passage may be enlarged by swinging the supplemental jaw on its pivot 29 from the full line position to the dotted line position shown in Fig. 1 for the purpose 40 of permitting larger and more irregular work-pieces or parts to be inserted between the punch and die than could possibly be inserted when said die is in its normal operative position. The supplemental jaw 45 is in the form of a lever which may be swung into and out of its operative position by manipulation of its rear end 33 which constitutes a handle. Suitable means may be employed for releasably holding the supplemental jaw in the operative position and at present I employ a spring-pressed plunger or locking bolt 34, shown in Fig. 5, carried by the supplemental lower jaw and adapted to enter a locating hole 35 in the 50 head 6 which determines the operative position of said jaw. A coiled spring 36 on the plunger acting at one end against the head of the latter and at the opposite end against a guide 37 which carries the plunger and 55 which in turn is fixed to the supplemental jaw, yieldingly holds the plunger 34 in its locating hole. The plunger may be withdrawn by means of a finger grip 38 on its outer end, thereby permitting the supplemental 60 jaw to be swung to the dotted line 65

position shown in Fig. 1 for widening the work-receiving opening. When the supplemental jaw is swung back the plunger 34 will snap in the locating hole 35 and rigidly hold said jaw in its operative position.

By reason of the lever formation of the supplemental lower jaw it may be quickly and conveniently manipulated. This is especially desirable in practice because punches of this kind are used on a great variety of work-pieces and the time element and convenience with which the punch is set in operative relation to the work-piece is an important factor in the practicability of such tool. This will be readily appreciated when it is considered that the lower jaw 9 must be moved twice each time the punch is used, that is, once for setting the punch in position and once for removing the punch. It will also be observed that the lever formation of the lower jaw affords a broad flat bearing surface against the lower jaw and head proper so that the supplemental jaw will be held in absolute alignment. The heavy pivot bolt and plunger provide a substantial support for the supplemental jaw adapted to carry the heavy punching pressures without deflection. The foregoing construction increases the utility of the punch by permitting its use on many types of work-pieces which heretofore were inaccessible with a punch of conventional construction.

It is believed that the foregoing conveys a clear understanding of the objects pre- 100 ficed above and while I have illustrated but a single working embodiment it should be understood that changes might be made in details of construction without departing from the spirit and scope of the invention as expressed in the appended claims, in which I claim—

1. A punch comprising a head having an upper punch-carrying jaw and a lower jaw spaced apart to provide a comparatively wide mouth, punch operating means mounted on the head, a lever pivoted on the lower jaw and providing a supplemental lower jaw having a die-carrying portion extending across the mouth formed by said upper and lower jaws with the die therein normally close to and aligned with the punch, and means for releasably holding the lever in an operative position with its die-carrying portion in alignment with the punch in order to permit swinging the supplemental jaw away to make the wider space between the main jaws available for entering a piece of work.

2. A punch comprising a head having an upper punch-carrying jaw and a lower jaw spaced apart to provide a comparatively wide mouth, punch operating means mounted on the head, a lever pivoted on the lower jaw and providing a supplemental

lower jaw extending somewhat above the plane of the lower jaw across the mouth formed by said upper and lower jaws, said lever having a broad flat side extending 5 rearwardly from said mouth and bearing against a complementary side of the lower jaw and head, a die-carrying portion on said supplemental lower jaw and means for releasably holding the supplemental lower 10 jaw in an operative position with its die-carrying portion in alignment with the punch.

3. A punch comprising a head having an upper punch-carrying jaw and a lower jaw 15 spaced apart to provide a comparatively wide mouth, punch operating means mounted on the head, a lever pivoted on the lower jaw and providing at its outer end a supplemental lower jaw extending in 20 its operative position substantially horizontally somewhat above the plane of the lower jaw across the mouth formed by said upper and lower jaws, a die-carrying portion 25 on said supplemental lower jaw, the inner end of the lever extending rearwardly beyond the head and providing a handle adapted to be manipulated for shifting the lever to raise said supplemental lower jaw into and out of operative position, and 30 means for releasably holding the lever with said supplemental lower jaw in an operative position on the head.

4. A punch comprising a head having an upper punch-carrying jaw, a lower jaw 35 and a handle, a punch slideable in said upper jaw, a punch-operating lever pivoted on the head, a die-carrying part pivoted on the lower jaws and adapted to be swung into

and out of operative position, in the latter of which positions to provide a greater clearance between the punch and die-carrying part, and means operative between the head and die-carrying part for releasably holding the latter in its operative position.

5. A punch comprising a head having an upper punch-carrying jaw and a lower jaw spaced apart to provide a comparatively wide mouth, a punch slideable in said upper jaw, a punch operating lever pivoted on the head, a die-carrying part pivoted on the lower jaw and having an upstanding die-carrying portion at its outer end positioned in proximity to and in alignment with said punch and adapted to be moved away from said position by pivotal movement of said part for widening the opening at the entrance to said mouth between the punch and die-carrying parts, and means for releasably holding said die-carrying part in its operative position.

6. A punch comprising a head having formed integrally therewith an upper punch guiding jaw and a lower jaw, a punch slideable in said upper jaw, punch-operating means mounted on the head, a supplemental jaw pivoted on said lower jaw and having an upstanding die-carrying portion extending into proximity to and alignment with said punch in the operative position of said jaw and being movable upon its pivot for withdrawing said die-carrying portion from said operative position for widening the entrance to said mouth, and means for releasably holding the supplemental jaw in said operative position.

GEORGE H. SPENGLER.
